UNITED STATES PATENT OFFICE.

WILLIAM B. LIPSCOMB, OF WASHINGTON, DISTRICT OF COLUMBIA.

STEAM ENGINE.

Application filed June 20, 1922. Serial No. 569,680.

The present invention relates to improvements in steam engines and particularly to improvements in the valve mechanism controlling the admission and exhaust of steam from the engine cylinder.

As the invention is especially adapted for use with locomotives, although some of the features thereof are adapted for use with other forms of steam engines, I have in the accompanying drawings illustrated its embodiment in a locomotive.

Referring to the invention, particularly as applied to a locomotive, an object thereof is to provide a valve mechanism which will be more efficient in operation than the slide valve and piston valve devices commonly in use.

A further object of the invention is to provide means whereby in event of injury to one head or end section of the driving cylinder of a locomotive an easily effected adjustment of the valve mechanism will enable the other chamber of the cylinder to function as usual, instead of rendering the entire cylinder useless.

The present invention, broadly considered, involves substituting for the slide valve or piston valve commonly employed to regulate the admission of steam alternately to the opposite ends of a locomotive driving cylinder a plurality of oscillating valves, two being shown, each controlling the supply of steam from one of the chambers of the driving cylinder.

More particularly, the invention includes a novel form of valve whereby steam passes through a cylindrical oscillating valve, on radial lines, to and from the port communicating with the engine cylinder. By this arrangement the same passage is utilized for conducting live steam to and exhaust steam from a cylinder so that there is no danger of the valve passages becoming clogged.

With the foregoing and other objects in view the invention consists in the construction and arrangement of parts that will be hereinafter fully pointed out and described in connection with the accompanying drawings, in which:

Figure 1 is a side elevation of a locomotive driving cylinder having an embodiment of my improved valve mechanism applied thereto.

Figure 2 is a front elevation of the parts

shown in Figure 1 and the forward end of 55 the locomotive boiler.

Figure 3 is a longitudinal vertical section through the valve chest and driving cylinder, on an enlarged scale.

Figure 4 is a similar section showing the 60 valves in a reversed position from that illustrated in Figure 3.

Figure 5 is a transverse section substantially on the line 5—5 of Figure 3.

Figure 6 is a transverse section on the 65 line 6—6 of Figure 3.

Figure 7 is a detail section of a portion of one of the valves, on an enlarged scale to show the packing or expansion strip.

Figure 8 is a perspective of a portion of 70 one of the valves, detached, the valve being in section.

In the drawings several of the parts are shown more or less conventionally and for the purpose merely of indicating the relative 75 positions of my improved valve mechanism to other parts of a steam locomotive, and it will be understood that, except where specifically referred to in the following claims, my invention is not to be understood as limited 80 to the exact form of the embodiment illustrated. That is, there can be various changes in the form and proportions of the parts illustrated without departing from the spirit or scope of the invention.

In the drawings, 1 indicates a driving cylinder of a locomotive within which a piston 2 is adapted to operate. The stem or rod 3 of the piston is connected by a pitman or driving rod 4 to a drive wheel 5 of the 90 locomotive. Such parts not being of my invention, it is not necessary to refer in further detail to the connection between the piston 2 and drive wheel 5. Any of the forms of such connections commonly in use 95 may be employed.

The cylinder 2 is provided with the usual ports 6, 7, through which steam is supplied to opposite sides of the piston 2.

In place of the ordinary slide or piston 100 valve and valve chest, I provide a valve chest which is interiorly divided into a steam supply chamber 8, an exhaust chamber 9 and two cylindrical valve seats, which are positioned between the chambers 8, 9 and each of which 105 is provided with a port 10 that communicates with the adjacent cylinder port, 6, 7. The valve chest is suitably attached to the cylin-

der 1 and other parts of the locomotive, and each of the valve seats therein is also provided with an inlet port 11 communicating with the steam chamber 8 and an exhaust port 12 that opens into the exhaust chamber 9. Steam is supplied to the steam space 8 from the boiler by a pipe 13 and the exhaust is conducted from the chamber 9 to the forward end of the locomotive, in the usual manner, by a conduit or pipe 14.

It will, of course, be understood that the arrangement of parts hereinbefore referred to and shown in the drawing are duplicated on the opposite side of the locomotive, and therefore, in the description of the invention only one set of valve devices is specifically referred to.

The ends of the valve seats are closed by heads 16, which are bolted to the ends of the valve chest and on such heads are formed the bearings which support the oscillatory cylindrical valves 17.

Each valve 17 comprises a cylindrical body, which is closed at its ends and provided with an intermediate transversely extending web 18. A shaft 19 extends through the ends of the valve 17 and the intermediate web, as well as through a suitable stuffing box 20 formed on one of the heads 16, and to its projecting end is attached a crank arm 21.

To facilitate movement of each valve in its seat, it is preferred to interpose anti-friction bearings 22 between the valve and bosses 35 or hubs formed on the inner faces of the heads 16 of the valve chambers.

Each valve is provided with an interior chamber or transversely extending passage, which extends across the axis of the valve and connects ports formed in the valve body and severally corresponding to the ports formed in the valve chamber wall. That is, each valve is provided with an inlet port 23, an exhaust port 24, and a port 25 which co-operates with the cylinder port 10 of the valve chamber. As shown, the port 25 is considerably wider than the ports 23 and 24, so that it will be in communication with the valve chamber port 10 when either the inlet ports of the valve and valve chamber are in communication or when the co-operating exhaust ports of the valve and chamber are in operative relation. It will thus be seen that the passage through the valve will be, when the parts are operating, constantly in communication with the cylinder port of the valve chamber, while the inlet and exhaust ports at the other end of the passage will be alternately connected with their respective ports in the valve chamber wall. Thus steam is supplied to the engine cylinder and exhausted therefrom through the port 25 and the passage in the valve.

As shown, it is preferred to make the several ports in the wall of the valve chamber

and the valve in the form of elongated slots which extend parallel to the axis of the valve, and in order to insure that the valve will fit the seat with sufficient closeness, to prevent leakage between the inlet and exhaust ports, it is preferred to provide each valve with an expansion strip 27 that is fitted in a groove extending throughout the length of the valve and beneath which strip a suitable leaf spring 28 is positioned. A similar strip may be arranged between the ports 23, 25.

The crank arms 21 are detachably connected, as by suitable bolts and removable nuts 30, with a valve trip rod 31 which is connected to the usual radius rod 32 and to a crank arm 33 on a rock shaft 34.

Any suitable means may be employed for reciprocating the valve trip rod 31. As shown, the radius rod 32 has a sliding engagement with a quadrant 35 pivotally supported on the locomotive frame at 36 and one end of which, by means of a link rod 37, is connected to a crank 38 on the main driving rod or pitman 4.

With this arrangement and with the parts positioned as shown in Figures 1 and 3, it will be seen that steam will be supplied from the chamber 8 through the ports 11, 23 of the left hand valve and the passage extending therethrough to the cylinder 6 and operate to move the piston 2 in the direction indicated by the arrow in Figure 3. At this time the exhaust ports 24, 12 of the right hand valve mechanism are in alignment, and, therefore, the steam exhausted through the cylinder port 7 will pass into the passage in the valve through the port in the right hand valve (Figure 3) through the port 25 and into the exhaust chamber 9.

As the piston approaches the limit of its right hand travel, the valve trip rod 31 will be actuated and the valves 17 oscillated to shift them from the positions shown in Figure 3 to those represented in Figure 4. This results in connecting the passage of the right hand valve (Figures 3 and 4) with the live steam space 8 and the exhaust port 24 of the left hand valve with the exhaust chamber 9. In this position steam will be supplied to the engine cylinder through the port 7 and the exhaust through the port 6 will pass into the passage in the left hand valve and through the ports 24, 12 to the chamber 9. It will be seen that the width of the ports 25 is such that both of said ports are constantly in engagement with the cylinder ports 6, 7, although the passage in the valve is alternately connected with inlet port 11 and exhaust port 12.

By means of a lever 40 connected through a link 41 with an arm 42 on the usual lift shaft 43, and the connection of said arm with the radius rod 32, the valves may be reversed, if desired, or adjusted so that they

will occupy a neutral position in which both the inlet and exhaust ports of each valve chamber will be cut off from the cylinder ports of said chamber.

5 An important feature of the invention is the facility with which the moving parts of the valves and the driving piston may be lubricated. An oil cup 50 secured to the top of the valve chest has its outlet extending to the steam space 8 and the lubricant discharged therefrom is carried by the steam into the valve seat and to the engine cylinder.

10 It is thought that the operation and advantages of the improvements will be readily understood from the foregoing description and drawings.

15 It will be seen that the invention provides a very compact and simple arrangement of parts by which the flow of steam to and from each end of the driving cylinder will be readily controlled. The valve construction is such that the valve is perfectly balanced at all times, the passage of steam therethrough being on a substantially diametrical line and a minimum amount of power is required to rock the valves in their respective seats. That is, the valve ends are not exposed to the direct boiler pressure, as has been the case in constructions heretofore proposed. The two inlet ports 11 are constantly open so that the same pressure is applied to both valves. Leakage of steam about the valves is also positively prevented.

20 The chamber within the valve and the several parts thereof are so shaped, proportioned and related that a minimum movement of the valve in its seat is required to connect the cylinder 1 with either the steam supply or exhaust chambers. This is of the greatest practical importance in a locomotive 25 valve mechanism. It will be appreciated that in a locomotive it is necessary that the inlet to the cylinder be opened to its maximum extent as nearly instantaneously as possible to avoid any delay in bringing the full volume of steam to act upon the piston.

30 In other forms of steam engines, it is not essential to have such a quick acting valve as is required for a locomotive, and, therefore, oscillating valves having the ports thereof relatively widely separated may be employed, necessitating a considerably greater extent of movement in passing from supply to exhaust position and vice versa.

35 Further, it is of great importance that the valve be of such form and so seated that movement thereof will be opposed by a minimum amount of friction or resistance. This is one of the main features of the construction herein described. By providing the valve with an interior chamber and arranging the ports in the particular relation shown, the pressure of the steam admitted to the chamber acts in all directions instead of acting to force the valve bodily laterally in the

direction in which it enters the valve, as is the case where the steam passage of the valve is formed only in the peripheral surface thereof.

40 Friction between the valve and its seat is also materially reduced by the efficient lubrication afforded by the construction described and shown. The oil being carried into the interior of the valve and out therefrom by the inlet and exhaust of steam, enters the space between the valve and its seat and maintains thorough lubrication of the adjacent surfaces.

45 One of the great advantages of the improved construction in its application to steam locomotives is the fact that an injury to one end or head of the driving cylinder does not result in disabling the engine completely as regards that cylinder. It is only necessary in case of such an accident to disconnect the crank arm 21 of the valve controlling the supply of steam to the damaged end of the cylinder from the valve trip rod 31 and, if necessary, rock the valve slightly to effectually close the inlet port 11 of its 50 cooperating valve seat. This will leave the other chamber of the cylinder, controlled by the valve connected to the trip rod 31, to function normally and the power of the locomotive is only reduced one fourth.

55 Another advantage of the improved construction as applied to a locomotive is that if the drive wheel 5 should be stopped in a position where the connection to the driving rod 4 is on a dead center due to a breakage of any portion of the valve gear, it is only necessary to manually reciprocate the valve trip rod on the broken side to adjust the valves on the other side of the engine to start.

60 Having thus described the invention, what is claimed is:

1. In a steam engine, the combination with a reciprocating driving piston and a cylinder surrounding the piston and having two ports communicating with its interior beyond the ends of the path of movement of the piston in either direction, of two valve seats of cylindrical form in cross section, each provided with an inlet port, an exhaust port, and a third port communicating with one of the ports of the driving cylinder, means for supplying steam to the inlet ports of both valve seats, and a tubular oscillatory valve in each valve seat having two ports, one adapted to connect the interior chamber of the valve with the valve seat inlet port only and the other adapted to connect said interior valve chamber with the exhaust port of the valve seat only, said valves being alternately brought into operative position by oscillation of the valve in its seat, the valve having also a third port connecting the aforesaid interior valve chamber with the intermediate port of the valve seat when

either the valve inlet or exhaust ports are operative, the said interior chamber of the valve constituting a common conduit for supplying live steam to the cylinder and for 5 the passage of exhaust from the cylinder.

2. In a steam engine, the combination 10 with a reciprocating driving piston and a cylinder surrounding the piston and having two ports communicating with its interior beyond the ends of the path of movement of the piston in either direction, of a valve casing 15 interiorly divided into a steam supply chamber, an exhaust chamber, and two valve seats of cylindrical form in cross section arranged on opposite sides of the steam supply chamber, each valve seat communicating with the supply chamber through an inlet port, and also having ports that communicate with the exhaust chamber and one of the ports of the driving cylinder, respectively, whereby a valve in the seat is subjected to exterior pressure from the steam supply chamber only through the area of 20 said inlet port, a tubular oscillatory valve in each valve seat having two ports, one adapted to connect the interior chamber of the valve with the valve seat inlet port only and the other adapted to connect said interior valve chamber with the exhaust port of the valve seat only, said valves being 25 alternately brought into operative position by oscillation of the valve in its seat, the valve having also a third port connecting the aforesaid interior valve chamber with the intermediate port of the valve seat when either the valve inlet or exhaust ports are 30 operative, the said interior chamber of the valve constituting a common conduit for supplying live steam to the cylinder and for the passage of exhaust from 35 the cylinder, 40

3. In a steam engine, the combination

with a reciprocating driving piston and a cylinder surrounding the piston and having two ports communicating with its interior beyond the ends of the path of movement of the piston in either direction, of a valve casing 45 interiorly divided into a steam supply chamber, an exhaust chamber, and two valve seats of cylindrical form in cross section 50 arranged on opposite sides of the steam supply chamber, each valve seat communicating with the supply chamber through an inlet port, and also having ports that communicate with the exhaust chamber and one of the ports of the driving cylinder, respectively, whereby a valve in the seat is subjected to exterior pressure from the steam supply chamber only through the area of 55 said inlet port, a tubular oscillatory valve in each valve seat having two ports, one adapted to connect the interior chamber of the valve with the valve seat inlet port only and the other adapted to connect said interior valve chamber with the exhaust port of the valve seat only, said valves being 60 alternately brought into operative position by oscillation of the valve in its seat, the valve having also a third port connecting the aforesaid interior valve chamber with the intermediate port of the valve seat when either the valve inlet or exhaust ports are 65 operative, the said interior chamber of the valve constituting a common conduit for supplying live steam to the cylinder and for the passage of exhaust from the cylinder, 70 and a lubricant duct extending into the steam supply chamber between the two valve seats. 75

In testimony whereof I have hereunto set my hand.

WILLIAM B. LIPSCOMB.
